[57] CLAIM

The ornamental design for a combined x-ray quality assurance test phantom and support stand, as shown and described.

DESCRIPTION

FIG. 1 is a perspective view of a combined x-ray quality assurance test phantom and support stand showing my new design;

FIG. 2 is a top plan view thereof;

FIG. 3 is a side elevational view thereof, with all other sides being identical to that shown;

FIG. 4 is a bottom plan view thereof;

FIG. 5 is a perspective view of the support stand with one tube shown fragmented for ease of illustration;

FIG. 6 is a side elevational view thereof, with all other sides being identical to that shown;

FIG. 7 is a top plan view thereof;

FIG. 8 is a bottom plan view thereof; and,

FIG. 9 is a perspective view of the test phantom and support stand in assembled condition with the protective caps on the test phantom removed.
